UNITED STATES PATENT OFFICE.

WOJCIECH WEGIEL, OF LUDLOW, MASSACHUSETTS.

DESIGN FOR A BASKET.

56,245.

Specification for Design.

Patented Aug. 31, 1920.

Application filed May 20, 1920. Serial No. 382,987. Term of patent 7 years.

To all whom it may concern:

Be it known that I, WOJCIECH WEGIEL, a citizen of Poland, residing at Ludlow, in the county of Hampden and State of Massachusetts, have invented a new, original, and ornamental Design for a Basket, of which the following is a specification, reference being had to the accompanying drawing, forming part thereof.

The figure is a view in perspective of a basket, showing my new design.

I claim:

The ornamental design for a basket, as shown.

WOJCIECH WEGIEL.
